KEY-SOCKET MECHANISM.

1,181,707

Specification of Letters Patent.

Patented May 2, 1916.

Application filed September 28, 1915. Serial No. 52,197.

To all whom it may concern:

Be it known that we, BENJAMIN C. WEBSTER and GEORGE P. KNAPP, citizens of the United States, residing at Bridgeport, county of Fairfield, State of Connecticut, have invented an Improvement in Key-Socket Mechanism, of which the following is a specification.

This invention relates to key sockets and has for its object to simplify and cheapen the construction of the switch mechanism and to improve its operation in use, especially in the matter of making a quick and snappy double make and break of the circuit, when the shaft is given a quarter turn in either direction.

With these and other objects in view, we have devised the novel switch mechanism which we will now describe, referring to the accompanying drawing forming a part of this specification and using reference characters to indicate the several parts.

Figure 1 is a view of a key socket, partly in elevation and partly in section; Fig. 2 a plan view of the switch mechanism complete, the upper insulating block being removed and the binding posts in section; Fig. 3 a similar view with the shaft, cam and connecting member removed; Fig. 4 a section on an enlarged scale on the line 4-4 in Fig. 2, looking in the direction of the arrows, the upper insulating block being in place, and the circuit open; Fig. 5 a similar view showing the position of the parts when the circuit is closed, and Fig. 6 is an inverted plan view corresponding with Figs. 4 and 5.

10 denotes the upper insulating block, 11 the lower insulating block, 12 the socket shell, 13 the cap, 14 the insulating lining, 15 the screw shell, 16 the center contact, 17 the shaft and 18 the cam which is loosely mounted on the shaft and is rotated thereby. All of the above parts may be of any ordinary or preferred construction.

It should be understood that the terms "upper" and "lower" as applied to the insulating blocks are relative only and are used for convenience in description.

50 19 denotes a binding post which we will term for convenience in description the positive binding post and which is formed integral with a plate 20 lying in contact with the screw shell. The screw shell and plate

are retained in place by means of screws 21 which pass through both insulating blocks. From the screw shell the current passes through the lamp, or other appliance, to the center contact which is in electrical connection with a contact plate 22 resting upon a ledge 29 on the lower insulating block.

23 denotes another contact plate which rests upon a ledge 30 on the lower insulating block, is secured thereto by a screw 24, and carries the negative binding post 25.

26 denotes a loose or floating connecting member which is socketed in the lower insulating block. We have shown the connecting member as made T-shaped at one end and V-shaped at the other end and the lower insulating block as recessed to correspond so as to loosely retain the connecting member in place but permit free vertical movement thereof. The special shape of the connecting member is not an essential feature of the invention, it being simply required that the member be so shaped as to bridge the space between contact plates 22 and 23, in order to close the circuit, and of sufficient length for engagement at approximately its mid-length by the cam. In the construction shown, the connecting member is provided with contact arms 31 which engage the contact plates, said arms and the contact plates being separated by an abutment 32 formed on the lower insulating block which renders arcing or sparking practically impossible.

27 denotes a spring socketed in the lower insulating block and bearing against the connecting member on the under side thereof, that is, on the side opposite to that engaged by the cam, and at a point in the longitudinal direction of the connecting member opposite to the point of engagement of said member with the contact plates. In other words, the cam engages the upper side of the connecting member at a point intermediate the points of engagement of the under side of said member with the contact plates and with the spring (compare Figs. 4 and 5). In the open circuit position (see Fig. 4), the spring end of the connecting member engages a projection 28 on the upper insulating block which lies in a corresponding recess in the lower insulating block. This projection, in the open

circuit position, serves as a fulcrum for the corresponding end of the connecting member.

The cam, as already stated, has a loose engagement with the shaft and when turned from the position shown in Fig. 5 toward the position shown in Fig. 4, completes the movement with a snap. The instant this snap action of the cam takes place, the spring will raise the connecting member, as in Fig. 4. The spring end of the connecting member engages the projection which acts as a fulcrum, causing the spring to lift the connecting member out of engagement with the contact plate, the action being that of a lever of the third class. When the cam is turned from the position shown in Fig. 4 toward the position shown in Fig. 5, the movement is likewise completed with a snap, although not quite as sharp as before, as the movement is against the power of the spring. The action of the cam in this movement is to force the contact end of the connecting member into electrical contact with the contact plates, the spring being compressed, and also to move the spring end of the connecting member out of engagement with the projection, as clearly shown in Fig. 5. This is an important feature, as it permits considerable variation in the height of ledges 29 and 30 upon which the contact plates rest and permits lateral tilting of the connecting member, if necessary when engaged by the cam, so that complete electrical contact with both contact plates is insured whenever the cam is turned to the closed circuit position.

Having thus described our invention, we claim:—

40 1. A mechanism of the character de-

scribed comprising contact plates, a floating connecting member, a fulcrum adapted to be engaged by said member, a cam for moving said member to the closed circuit position, and a spring acting, when the cam 45 is turned to the open circuit position, to move the connecting member into engagement with the fulcrum and out of engagement with the contact plates.

2. A mechanism of the character de- 50 scribed comprising two contact plates, ledges upon which they rest, a floating connecting member, a fulcrum adapted to be engaged by said member, a cam for moving said member out of engagement with the 55 fulcrum and into electrical contact with both contact plates, said member tilting laterally should the ledges be of varying height, and a spring acting to move said member out of engagement with the contact plates.

3. A mechanism of the character de- 60 scribed comprising a lower insulating block, contact plates secured thereto, a floating connecting member T-shaped at one end and 65 V-shaped at the other end, which is recessed into said block, a spring acting to raise said member to the open circuit position, a shaft, and a cam loosely mounted on the shaft and rotated thereby, by which the connecting member is moved to the closed circuit position against the power of the spring.

In testimony whereof we affix our signatures.

BENJAMIN C. WEBSTER.
